MULTICOLOR ROTARY PRINTING PRESS

Filed June 21, 1930

UNITED STATES PATENT OFFICE

HOWARD M. BARBER, OF PAWCATUCK, CONNECTICUT, ASSIGNOR TO C. B. COTTRELL & SONS COMPANY, OF WESTERLY, RHODE ISLAND, A CORPORATION OF DELAWARE

MULTICOLOR ROTARY PRINTING PRESS

Application filed June 21, 1930. Serial No. 462,771.

The successful operation of a multicolor printing press calls for long continuous runs of the press after its plate cylinders have been made ready. The product of such a press for the most efficient use of the press should also be printed in the maximum number of colors for which the press is designed. Frequently, the product from a multicolor printing press far exceeds the intermediate shipping requirements for the product, thus rendering it necessary to store large quantities of the printed stock with the consequent storage and handling expense.

The object of my invention is to provide means whereby a multicolor printing press may be used to the fullest extent by providing means for silencing one or more of the plate cylinders so that different jobs of less than the full color capacity of the press may be run successively and, if desired, alternately in less than the full run of any particular product of the press, to meet the desired product requirements and thereby eliminating the necessity of storing excessive amounts of the stock of any one job. Furthermore this ability to silence one or more of the plate cylinders not only permits the printing of a product in less than the full number of colors but also permits the running of different products with the same colors or with different colors, and also permits the silenced plate cylinder or cylinders to be made ready while the remaining plate cylinder or cylinders are being used.

My invention is illustrated in connection with a four color rotary printing press in which the four plate cylinders coact with a common impression cylinder.

A practical embodiment of my invention is represented in the accompanying drawings, in which

Fig. 1 represents a detail side elevation, partly in section, of so much of a four color rotary printing press as embodies my invention, two of the plate cylinders being shown in operative position and two silenced, and

Fig. 2 represents a detail front view, partly in section, of one of the plate cylinders and its silencing mechanism.

The impression cylinder 1 has its shaft 2

mounted in suitable bearings 3 in the boxes 4 of the side frames 5 of the press. Four plate cylinders 6, 7, 8 and 9 are shown arranged around the upper side of the impression cylinder 1 with their respective shafts 10, 11, 12 and 13 mounted in suitable bearings 14, 15, 16 and 17 in boxes 18, 19, 20 and 21 of the side frames 5.

The impression cylinder 1 is provided with the gear 22 which meshes with the gears 23, 24, 25, 26 of the respective plate cylinders 6, 7, 8 and 9 when the plate cylinders are brought into coaction with the impression cylinder.

Similar means are employed for independently moving each of the plate cylinders radially into and out of coaction with the impression cylinder. Therefore, only one of these means will be described in detail, viz. the one for moving the plate cylinder 6, as this will give a clear understanding also of the operation of all of the other plate cylinder moving means.

The bearings 14 of the shaft 10 of the plate cylinder 6 may be moved inwardly and outwardly along the boxes 18 to bring the plate cylinder into and out of coaction with the impression cylinder by bringing the plate cylinder gear 23 into and out of mesh with the impression cylinder gear 22 as follows:

Each bearing 14 is provided with an outwardly projecting screw 27 on which is threaded a worm wheel 28 which meshes with a worm 29 on a short cross shaft 30 rotatably mounted in the box cap 31. This cross shaft 30 is provided with a gear 32 which meshes with a gear 33 mounted on a stud shaft 34 carried by a bracket 35 projecting from the box 18. This gear 33 in turn meshes with a gear 36 on the hand shaft 37 which is herein shown as extending across the machine and as common to both gears 33. This shaft 37 is shown as having a crank handle 38 for the simultaneous manual operation of both of the shaft bearings 14.

Similar means are employed for independently ensuring the accurate return of each of the plate cylinders to its adjusted coactive relationship with the impression cylinder after the plate cylinder has been once ad-

justed and then moved away from the impression cylinder for silencing the plate cylinder. One only of these means will be specifically described, viz. the one applied to the cylinder 6.

Stops 39 and 40 are rotatably adjustable with respect to their gears 32 and 33 respectively so that when the plate cylinder 6 has been adjusted into its proper kissing contact with the impression cylinder 1, the stops may be swung around on their respective shafts 30 and 34 to bring their noses into engagement with each other and there locked to prevent further inward movement of the plate cylinder.

The means which I have shown for locking the stops 39 and 40 in their adjusted positions comprises locking bolts 41 and 42 which are passed through selected holes of a concentric series of holes 43 and 44 in the gears 32 and 33 respectively. These locking bolts also pass through elongated grooves 45 and 46 in their respective stops 39 and 40, which grooves are concentric with the axes of said gears 32 and 33 and register with the concentric series of holes 43 and 44 respectively.

From the above description it will be seen that the usefulness of the press is materially enhanced by providing means for silencing one or more of the plate cylinders at pleasure. This feature allows the remaining plate cylinder or cylinders to be used for printing a job or part of a job while the silenced plate cylinder or cylinders may be made ready for another job or may be held in readiness for printing another job. Furthermore, the printing press is capable of printing a job in any number of colors up to the maximum and it is also capable of printing two jobs in the same color or colors or in different colors and combinations of colors as desired, thus rendering the press practically universal in its operation.

It is evident that various changes may be resorted to in the construction, form and arrangement of the several parts without departing from the spirit and scope of my invention, and hence I do not intend to be limited to the particular embodiment herein shown and described, but

What I claim is:—

1. In a rotary printing press, an impression cylinder, a plate cylinder, means for moving the plate cylinder into and out of printing contact with the impression cylinder and adjustable means carried by said plate cylinder moving means for ensuring the accurate return of the plate cylinder to its printing contact with the impression cylinder when moved away therefrom.

2. In a rotary printing press, an impression cylinder, a plate cylinder, means for moving the plate cylinder into and out of printing contact with the impression cylinder, and a pair of devices carried by said

plate cylinder moving means adjustable into engagement with each other for ensuring the accurate return of the plate cylinder to its printing contact with the impression cylinder when moved away therefrom.

3. In a rotary printing press, an impression cylinder, a plate cylinder, means for moving the plate cylinder into and out of printing contact with the impression cylinder, and means for ensuring the accurate return of the plate cylinder to its printing contact with the impression cylinder when moved away therefrom, comprising a pair of stops rotatively adjustable into engagement with each other and means for locking the stops in their adjusted positions.

4. In a rotary printing press, an impression cylinder, a plate cylinder, means for moving the plate cylinder into and out of printing contact with the impression cylinder, and means for ensuring the accurate return of the plate cylinder to its printing contact with the impression cylinder when moved away therefrom, comprising a pair of meshing gears, stops rotatively adjustable on the axes of said gears into engagement with each other and means for locking the stops in their adjusted positions.

5. In a rotary printing press, an impression cylinder, a plate cylinder, means for moving the plate cylinder into and out of printing contact with the impression cylinder, and means for ensuring the accurate return of the plate cylinder to its printing contact with the impression cylinder when moved away therefrom, comprising a pair of meshing gears, stops rotatively adjustable on the axes of said gears into engagement with each other and means for locking the stops in their adjusted positions including a concentric series of holes in each gear, a concentric groove in each stop registering with said holes and a locking bolt engaging said groove and a selected hole.

In testimony, that I claim the foregoing as my invention, I have signed my name this 18th day of June, 1930.

HOWARD M. BARBER.
